UNITED STATES PATENT OFFICE.

FRED EVANS, OF SUMMIT, NEW JERSEY, ASSIGNOR TO LOUIS V. ARONSON, OF NEWARK, NEW JERSEY.

FLASH LIGHT.

Application filed March 22, 1920. Serial No. 367,926.

To all whom it may concern:

Be it known that I, FRED EVANS, a citizen of the United States, residing in the city of Summit, in the county of Union and State 5 of New Jersey, have invented certain new and useful Improvements in Flash Lights, of which the following is a full, clear, and exact description.

My present invention relates to improvements in pocket flash-lamps and it consists 10 in the details of construction and in the arrangement and combination of parts herein described and claimed.

The paramount object of my invention is 15 to provide mechanism whereby, through the reciprocating movement of a push-rod, to impart continuous movement to the train of speed multiplying gears required for the actuation of the current generator.

20 A further object of my invention is to provide certain features of improvement in the manner of making contact with the lamp terminal.

Other objects and advantages will appear 25 in the following specification, and my invention is illustrated in the accompanying drawing forming part of this application, in which:—

Fig. 1 is an elevational view of my improved flash-lamp with the front casing section removed, showing the arrangement of the interior parts.

Fig. 2 is a central longitudinal sectional view.

35 Fig. 3 is a horizontal cross-section, taken on line 3—3 of Fig. 1.

In carrying out the present invention, I prefer to employ an elongated casing having rounded ends, the same being made up 40 of complementary sections, cast from iron aluminum, or other suitable material. Thus, in the accompanying drawing, 4 represents the elongated section for the front of the casing, being cast with rounded ends 5 and 6, and with a side flange 7 all around. 8 represents the elongated rear section, similarly cast with rounded ends and with a side flange 9 all around. Centrally of the rounded end 5, the meeting flanges 7 and 9 45 are each cast with one-half of the circular opening 10. The meeting edges of the flanges 7 and 9 are cast or otherwise made with overlapping tongues 11, which are provided with suitable threaded openings for

the reception of screws as 12, whereby the 55 sections are securely united.

Arranged between the front and rear plates 4 and 8, immediately behind the opening 10, is a reflector 13, which is formed with an axial socket 14, in which is screw-threaded the base of an incandescent lamp 15. This reflector carries a lens 16 formed on its outer side with a convex surface which projects through the opening 10 as shown, and which is designed to intensify 60 the rays of light. Below the reflector socket 14, the plate 8 is cast with a projection 17 having a forked end for the reception of a spool-shaped element 18, consisting of nonconducting material; the opposing 65 flanges 19 of this element engaging over the top and bottom faces of the forked end, as best shown in Fig. 1. The vertical body 70 of the element 18 is provided with a bore 20 in which is seated a tubular pin 21, formed with a head designed to engage a terminal 75 of the lamp base. Coiled around this pin is a spring 22, which is confined between the bottom of the bore and the head of the pin, so as to urge the pin into tight engagement 80 with the lamp terminal.

For supporting the remainder of the working parts, I provide a plate 23, which extends upwardly from the flange 7 alongside the front plate 4, centrally thereof, and 85 which is connected with the rear plate 8 by the arbors 24, 25 and 26, arranged in parallelism as shown. Extending across the casing and through suitable openings provided in the flange 9 is a push-rod 27 whose 90 intermediate portion consists of the rack-bars 28 and 29. The rack-bar 28 extends above the arbor 24 and has its toothed edge in engagement with a pinion 30 loose on said arbor; while the rack-bar 29 crosses below 95 the arbor 24 and has its toothed edge in engagement with a pinion 31 also loose on said arbor. Both pinions 30 and 31 have ratchet teeth cut in their faces. Fast on the arbor 24, adjacent the pinion 30, is a collar 32 in 100 which is set a pin 33 normally urged by a spring 34, into engagement with the ratchet teeth of its pinion. In like manner another collar 35 having a spring urged pin 36, is provided for the pinion 31.

When, under this construction, the push-rod 27 is thrust to the right, the pinion 30 is turned to the right, while the pinion 31

is turned to the left; and, conversely, when the said push-rod is thrust to the left, the pinion 30 is turned to the left, while the pinion 31 is turned to the right. Now, during the turning of the pinion 30 to the right, the arbor 24 is turned in a similar direction because of the engagement of the pin 33 with the ratchet teeth of this pinion; and in this instance the pin 36 is not active on its pinion since it yields from the teeth thereof. On the other hand, during the movement of the pinion 31 to the right, the arbor 24 is turned to the right because of the engagement of the pin 36 with the ratchet teeth of its pinion; and in this instance, the pin 33 is not effective since it yields over the ratchet teeth of its pinion. In other words, under the thrust of the push-rod 27, either to the right or to the left, the arbor 24 is turned to the right. At each end of the intermediate rack-bars, a spring 36' is coiled about the push-rod 27, the purpose being to re-position the latter automatically after each thrust, whether made to the right or the left.

Fast on the arbor 24 is a gear wheel 37 with which is connected a pinion 38, in mesh with a gear wheel 39, fast with a pinion 40 on the arbor 25. The gear wheel 39 meshes with a pinion 41, fast with a ratchet wheel 42 on the arbor 26. Loosely mounted on the arbor 26 is a permanent magnet 43, formed with branches 44, between which are a series of armatures 45, coil wound in series, and attached to a guard sleeve 46, which is made solid with the rear plate 8. Pivoted at 47 to a branch of the magnet is a pawl 48, which is held in engagement with the teeth of the ratchet wheel by means of a spring 49, pinned at 50 to a magnet branch. Through this train of speed multiplying gears, the continuous movement of the arbor 24 is utilized to cause the magnet 43 to spin around the armature coils and set up a current. One end 51 of the winding leads to a

binding post 52, which is screw-threaded into the spool-shaped insulation 18, in position to engage the interior of the pin 20, and so conduct the current to the lamp terminal. The other end 53 of the winding is grounded on the casing at 54; to which point the return from the lamp is effected through the lamp base, the reflector and the casing.

The push-rod 27 may be conveniently actuated by the thumb of the hand in which the flash-lamp is carried; and from the foregoing description, taken in connection with the accompanying drawing, it will be understood that a continuous flash may be obtained by actuating the push-rod repeatedly in quick succession.

Having thus described my invention, what I claim is:

The combination of a casing consisting of complementary sections provided with an opening, of a reflector and an incandescent lamp supported in said opening, one of said sections being provided with supporting means, contact making means for said lamp removably located on said supporting means, a gear train supported in said casing including an arbor, of a pair of pinions loosely mounted on the arbor and having ratchet teeth cut in their faces, a collar for each pinion fast on the arbor and provided with a spring urged pin in engagement with the ratchet teeth of its pinion, and a reciprocal push-rod arranged at right angles to said arbor extending through said casing and formed with rack-bars extending one above and one below said arbor and engaged each with a pinion, whereby upon movement of the push-rod in either direction the arbor will be moved only in one direction.

This specification signed and witnessed this eighth day of March, 1920.

FRED EVANS.
